BUILDING CONSTRUCTION

Walter S. Rugg and Henry D. James,
Pittsburgh, Pa.

Application February 29, 1936, Serial No. 66,435

6 Claims. (Cl. 189—1)

The present invention relates to a building construction and more particularly to a construction of the multiple-unit type the units of which are largely pre-fabricated before shipment to the building site.

Considerable work has been done heretofore on the so-called pre-fabricated type of building, but such work has been generally unacceptable to prospective customers, except for cheaper grades of houses, garages, etc. The size to which such structures could be safely erected was limited, there was a lack of attention to proper thermal insulation, the method of securing the outer or facing material was more or less unsightly and inconvenient to apply, and the overall appearance of the structure was such that it was generally unacceptable in competition with buildings or homes built in the conventional manner.

The only alternative, to the prospective builder, is to resort to usual construction methods involving a substantial labor expense and a long period, of uncertain duration, for erecting the building.

It is an object of the present invention to provide an improved building structure and method of erecting and assembling it which overcomes the objectionable features of known structures and methods; which results in a rigid structure which is economical to construct and erect; which lends itself readily to the production of buildings, dwellings, and the like, competitive in appearance with usual architectural designs; which may be readily taken apart, without damage to the parts, to facilitate alteration of the building shape or repair and replacement of the parts; and which has complete thermal insulation between the interior and exterior walls thereof.

Other objects of the invention will be apparent from the following description read in conjunction with the accompanying drawings wherein:

Figure 1 is a view in vertical section as viewed from the rear of a wall unit in accordance with the present invention;

Fig. 2 is a view in section taken on the line II—II of Fig. 1;

Fig. 3 is a view in section taken on the line III—III of Fig. 1;

Fig. 4 is a view in section taken on the line IV—IV of Fig. 2;

Fig. 5 is a view in vertical section as viewed from the rear of a wall unit of modified construction;

Figs. 6 and 7 correspond to Figs. 2 and 3, taken on the lines VI—VI and VII—VII of Fig. 5, respectively;

Figs. 8, 9 and 10 are views in perspective, with parts broken away, of structural elements shown in the preceding figures;

Fig. 11 is a view in horizontal section showing further details of the construction embodying the invention; and

Fig. 12 is a fragmentary top view of a modified unit shown in Figs. 3 and 7.

Referring more specifically to the drawings, the building structure comprises a foundation or other support (such as 2 in Fig. 6) having an H-beam 4 resting thereon and suitably secured thereto with a relatively wide upper bearing surface for supporting the wall units and floor beams 6.

Each of the floor beams 6 comprises a metal girder of I-shape having one end thereof resting upon the H-beam 4, at right angles thereto, and having portions of the upper flange cut away as indicated in Fig. 10, for the purpose herein-after described.

The primary element of each building unit comprises a one-piece structural iron framework of open or "crate" construction, made of angle irons 13 welded at their points of juncture as indicated in Fig. 8. All of the angle irons face inwardly, toward the center of the framework and constitute a readily portable and unusually rigid construction. If for any reason increased rigidity and strength is required, bracing members may be provided, such as angle strips 12, welded or otherwise secured thereto.

As shown in Fig. 2, each building unit, or framework, is mounted upon the supporting H-beam 4 with the lower corners thereof upon the lower flange of a floor beam 6; the cut-away upper flange of which permits the frame edges to lie against the web of the beam 6.

Bolts 14, or other suitable means, are then used to clamp the lower angle members 10, the lower flange of I-beam 6 and the upper flange of H-beam 4 in rigid relation. Further, bolts 16, extend through the side angle members 13, the web of beam 6 and the side angle of an adjacent frame unit, to rigidly connect adjacent units.

A bracing member 12, as shown in Fig. 2, is disposed transversely of the frame so that the upper face is substantially level with the upper flange of I-beam 6 to constitute a continuous support for flooring 18, and another member 12 is at the top of the frame to engage a similar member 12 at the lower edge of the frame next above.

As shown in Fig. 1, spacing blocks or strips 20,

of any desired material, are preferably disposed between the framework and the H-beam 4, and between adjacent frames, to increase the rigidity of the structure, and permit, through the use of 5 spacers of selected thickness, proper alignment of all elements of the structure to compensate for manufacturing discrepancies.

When the frame units are in position, or a 10 desired number of them, the outer surface of the wall is covered with facing units 22 of desired construction but preferably of a size corresponding to the length and width of the frame units, or 15 multiples of such dimensions. As shown in Fig. 3, a facing unit may comprise, for example, and 20 not by way of limitation, an outer surface 24 of a tough weather-resistant material the face of which may be cut or otherwise marked to simulate stone, brick, or any desired finish, and a layer of filler 26 of thermal insulating material. 25 The portions 24 and 26 are formed integrally and sheets so formed are readily available. It is intended, however, that any desired material may be employed for this purpose without departing from the spirit of the invention. For example, 30 the units 22 may consist of a metal sheet having thermal insulation on its inside and a weather-proof surface attached to the outside, or as indicated in Fig. 12, the facing unit may comprise a sheet metal base or rear face 27 which carries 35 with it thermal insulation and weather-resistant material as in Fig. 3. Clips 29 may then be employed to clamp the unit to the structural members 10, as indicated.

One method of securing the facing units to the 35 frame is shown in Fig. 3, comprising an elongated strip 28, of at least the length of the units for overlying the joint between adjacent units. Each strip is provided, integrally therewith, with a longitudinal flange 30 (Fig. 9) for insertion between 40 the adjacent units, and apertured projections 32 extending beyond such flange. Such projections 32 are of sufficient length to project, when the strip is in operative position, beyond the edge of the front frame members 10 to expose 45 each aperture for the reception of a pin, wedge, or other desired instrumentality 34, to draw the strip firmly against the face of the facing units 22 in weather tight relation. Preferably the strips 28 are of non-metallic material having a low thermal 50 conductivity. However, if the strip 28 and its flange 30 are metallic, the projecting portions 32 are of insulating material secured to the flange 30 by U-shaped rivets 33, as indicated in Fig. 9. By reason of either type of construction, there is 55 no path for exterior ambient temperatures to be conducted through the wall to the interior of the building, as is the case with all structures of this general character of which we have knowledge. If the strips 28 were not thermally insulated, the 60 outside temperature would be conducted through them into the framework 10 and the interior wall to such extent that the advantage of heat insulation in the facing unit, or behind it, is largely vitiated, and moisture would condense on the interior structure. Additional strips of the same material as the strips 28 may extend horizontally 65 across the face of the panels and be secured thereto by clamping their ends under the face of adjacent strips 28, to subdivide the surface into any desired pattern.

Another method of securing facing units to the 70 frames 10 is shown in Figs. 5, 6 and 7. Here the unit 40 comprises a face 42 of weather resistant material and thermal insulation 44, and is provided with blocks 46, of a material suitable to

hold stud bolts or screws 48, molded into the unit in position to align with apertures in clamping strips 50. As shown, the ends of the strips 50 overlie the flat inner faces of the strips 10 so that when the studs are screwed down the plate 40 is drawn firmly against the frame. It is possible by this construction to obtain a tight butt-joint between the edges of adjacent plates 40, but to further insure a weather-tight fit, the insulation layer 44 may be bevelled to provide space 10 for suitable caulking, cement, or the like, 52, which is applied before the plates are clamped, the bevelled construction insuring that the material 52 will be compressed and properly distributed. 15

As indicated in Fig. 6, certain of the floor beams 6 may be extended beyond the face of the wall to constitute a support for a porch, thereby tying in the porch construction with the rest of the building in a desired manner. Obviously, as many 20 of the wall units as desired may be provided with window sashes, door frames, etc., depending upon the architectural effect desired.

Thus far, the description has dealt with only the face of the building perpendicular to the floor 25 beams 6. Walls at right angles thereto may be mounted in a similar manner, as shown in Fig. 11. A structural unit 60 for the corner of the building, comprises essentially two units such as 10 at right angles and is pre-fabricated in a manner similar to the units 10. It consists of a plurality of angle strips 61 assembled and welded, to the shape shown, with suitable bracing strips 62 corresponding to the strips 12 of the previous 30 figures. 35

One leg of the corner unit 60 is secured to the adjacent unit 10 and the end of the floor beam 6 in the manner above described, and the other leg, constituting the beginning of a side wall extending rearwardly and to the left of the wall indicated in Figs. 3 and 7, is secured to an adjacent section 10 and the end of a short transverse I-beam 63 the other end of which is secured, by angle plates 64 bolted or welded to the web of the main floor beam 6. Preferably the height of the transverse I-beam 63 is such that the inner end fits between the upper and lower flanges of the beam 6. The outer end of the beam 63 has its upper flange removed for insertion between the units 10 and 60, as in the case of the beams 6, it being understood that the number of transverse beams 63 correspond to the number of panels or units constituting the side wall of the building. 40 45 50

Certain of the transverse beams 63 may be extended through the wall structure to constitute a support for a porch or other outside structure, in which event the floor level of such structure will be slightly below that defined by the floor beams 6 which is desirable for weather-protective 55 purposes. 60

It should be apparent, from the foregoing, that the construction described has many advantages. The open construction of the framework 10 permits the ready insertion of plumbing, wiring, etc. through the walls, and in fact provides a structure which may readily be used for ducts for air heating or conditioning. On the other hand, the open or crate-like construction facilitates the securing of the facing units 22 and 40 to the framework. All of such fastening means being accessible only from inside the building, is in itself a substantial advantage facilitating the erection of the building and not being exposed to exterior weather conditions. 65 70 75

It should also be apparent that although the invention results in an unusually rigid construction for this type of building, it may readily be disassembled for repair or replacement of parts, or to alter or expand the structure as desired.

Quite obviously, various modifications may be made in the construction shown and described without departing from the invention, and it is desired that the invention be limited only by the prior art and appended claims.

We claim as our invention:

1. A multiple unit wall assembly for a building construction comprising a foundation support, a plurality of structural elements and means for mounting them in edge to edge relation on said support to constitute the framework for said wall, floor beams at right angles to a wall of said foundation support each having an end portion extending between two adjacent structural elements and means for securing such elements thereto, a covering of weather resistant material for the outer surface of said wall and means for securing it to said structural elements, said floor beams having upper and lower flanges with the upper flange of the end portion removed to permit insertion between adjacent structural elements, adjacent corners of said elements resting upon the lower flange of said end portion.

2. In a multiple unit wall assembly for a building construction including a foundation shaped to support two walls at right angles to each other, a plurality of pre-fabricated structural elements disposed in edge-to-edge relation to constitute the framework of said walls, a plurality of floor beams extending perpendicularly to one of said walls and having end portions interfitted between adjacent structural elements, and short beams extending perpendicularly to said floor beams having the outer ends thereof interfitted between adjacent structural elements of the other wall, and means for securing the inner ends of said short beams to a floor beam.

3. In a multiple unit wall assembly for a building construction including a foundation shaped to support two walls at right angles to each other, a plurality of pre-fabricated structural elements disposed in edge-to-edge relation to constitute the framework of said walls, a plurality of floor beams extending perpendicularly to one of said walls and having end portions interfitted between adjacent structural elements, and short beams extending perpendicularly to said floor beams having the outer ends thereof interfitted between adjacent structural elements of the other

wall, and means for securing the inner ends of said short beams to a floor beam, said floor beams having upper and lower flanges and the upper flange of the end portions being removed to permit insertion between adjacent structural units.

4. In a multiple unit wall assembly for a building construction including a foundation shaped to support two walls at right angles to each other, a plurality of pre-fabricated structural elements disposed in edge-to-edge relation to constitute the framework of said walls, a plurality of floor beams extending perpendicularly to one of said walls and having end portions interfitted between adjacent structural elements, and short beams extending perpendicularly to said floor beams having the outer ends thereof interfitted between adjacent structural elements of the other wall, and means for securing the inner ends of said short beams to a floor beam, said short beams being of less height than the floor-beams.

5. In a multiple unit wall assembly for a building construction including a foundation shaped to support two walls at right angles to each other, a plurality of pre-fabricated structural elements disposed in edge-to-edge relation to constitute the framework of said walls, a plurality of floor beams extending perpendicularly to one of said walls and having end portions interfitted between adjacent structural elements, and short beams extending perpendicularly to said floor beams having the outer ends thereof interfitted between adjacent structural elements of the other wall, and means for securing the inner ends of said short beams to a floor beam; certain of said short beams being extended beyond the face of said other wall for supporting a structure on the outside of the wall.

6. In a multiple unit wall for a building construction, a plurality of pre-fabricated structural elements and means for mounting them to constitute the frame-work for a wall, a plurality of panels of weather-resistant material in substantially edge-to-edge relation constituting the exterior surface for said wall, means for mounting said panels in such relation including means extending between adjacent panels and overlapping the joint therebetween and having portions extending between adjacent structural units and means for exerting a wedging action thereon to draw said panels firmly against the structural elements.

WALTER S. RUGG.

HENRY D. JAMES.
